DESIGN FOR A HOLDER FOR SHAKERS OR THE LIKE

Gunnar Madvig, Alameda, Calif.

Application July 24, 1935, Serial No. 57,794

Term of patent 3½ years

To all whom it may concern:

Be it known that I, Gunnar Madvig, a subject of the King of Denmark and a resident of the city and county of Alameda, and State of California, have invented a new, original, and ornamental Design for a Holder for Shakers or the like, of which the following is a specification, reference being had to the accompanying drawing, forming part thereof.

I claim:

The ornamental design for a holder for shakers or the like, substantially as shown.

GUNNAR MADVIG.
